UNITED STATES PATENT OFFICE.

FLORENCE PRETZ, OF KANSAS CITY, MISSOURI.

DESIGN FOR AN IMAGE.

No. 39,603.

Specification for Design.

Patented Oct. 6, 1908.

Application filed June 9, 1908. Serial No. 437,599. Term of patent 7 years.

To all whom it may concern:

Be it known that I, FLORENCE PRETZ, a citizen of the United States, residing at Kansas City, in the county of Jackson and State of Missouri, have invented a new, original, and ornamental Design for Images, of which the following is a specification, reference being had to the accompanying drawing, forming part thereof.

The figure is a front elevation of an image, showing my new design.

I claim:

The ornamental design for an image, as shown.

FLORENCE PRETZ.
